UNITED STATES PATENT OFFICE.

SAMUEL DAVIS, OF NEW YORK, N. Y.

MINER'S-LAMP SUPPORT.

SPECIFICATION forming part of Letters Patent No. 680,133, dated August 6, 1901.

Application filed October 13, 1900. Serial No. 32,994. (No model.)

To all whom it may concern:

Be it known that I, SAMUEL DAVIS, a citizen of the United States, residing at Manhattan borough, in the city, county, and State of New York, have invented new and useful Improvements in Miner's-Lamp Supports, of which the following is a specification.

By means of this invention a lamp can be connected to a hat or cap, so as to be free to swing forward and back and also laterally and to be automatically or permanently in vertical position; so as to avoid accident or spilling and secure satisfactory illumination.

This invention is set forth in the following specification and claims and illustrated in the annexed drawings, in which—

Figure 1 is a side elevation of a lamp-holder. Fig. 2 is a perspective view of the holder shown in Fig. 1. Fig. 3 is a sectional view of the holder. Fig. 4 is a section along $\alpha\alpha$, Fig. 3. Fig. 5 shows a pad. Fig. 6 shows a modification. Fig. 7 shows a lamp-hook padded or made noiseless.

To the hat or cap is connected the base-piece a of the lamp-support, said base being readily formed from a suitable piece of material or sheet metal and adapted to be riveted or secured to the cap or hat. An arm b has a pivot or swivel connection c with the base and has an eye d and slot e for engaging and steady-
ing a lamp-hook f , the free end of the hook being slipped into the eye and the shank in or vertical part of the hook seating itself in or
below the slot e or the vertical branch of such slot. The arm will hold the lamp perma-
nently or automatically in vertical position,
so as to allow the lamp to swing forward and laterally, with the center of gravity of the lamp
below pivot c . The arm has upper or hori-
zontal flanges g and vertical flanges h , said arm being of angular or bent shape, as seen. The hook f in eye d and slot e , sitting between these flanges g and h , is held steadily to the arm, and as the latter swings from side to side or swivels about pivot c the lamp and arm move together.

In order to prevent the lamp when moved or jolted from producing any click or noise that might disturb a miner, especially when on the lookout for possible cracking or fall-
ing of the ceiling or wall in a mine, a noise-
killer or pads can be supplied. Soft pads or

bands i , seated about or projecting beyond the flanges g and h , will act to dampen or deaden noise. A pad or buffer k at the foot of slot e 55 will deaden or ease a blow or impact of the lamp.

To prevent noise or creaking of pivot c , a suitable noise-killer can be applied—as, for example, soft pads or washers l' , as seen in Fig. 6, or a soft tube or sleeve l , as seen in Fig. 3—to prevent direct contact or rubbing of the pivot directly against the holder or base a .

The pivot can be made non-binding or 65 easily rotatable by making the rivet-disk m convex and also having the head of the rivet of what may be called "conical" or "frus-
tum" shape.

The hook f of the lamp might also be made 70 noiseless or have a soft sleeve or tube slipped thereon, as seen in Fig. 7.

Should it be desired at times to prevent swinging, a hook or locking device n could be made to engage the arm and prevent rotation 75 about pivot c .

The lower edge of the arm at the foot of slot e could be bent or rounded, so as not to cut the pad k .

What I claim as new, and desire to secure 80 by Letters Patent, is—

1. A lamp-support consisting of a base-piece and an arm made to swivel or pivot on the base and extended downward from such pivot to support a lamp with its center of gravity 85 below the pivot substantially as described.

2. A lamp-support consisting of a base-piece and a swiveling arm on the base, said arm ex-
tended downward and having an eye and slot 90 for engaging and steadyng a lamp-hook sub-
stantially as described.

3. A lamp-support consisting of a base, and a pivoted arm having an opening d and a slot below the pivotal point of the arm, and a flange for steadyng the lamp arranged at 95 each side of the slot.

4. A lamp-support consisting of a base, an arm and a pivot for the arm, said pivot hav-
ing a convex or non-binding washer made to 100 bear against the base substantially as de-
scribed.

5. A lamp-support comprising a base, a downwardly-extending arm pivotally connected thereto and provided with a slot and

opening for supporting the lamp, and a lock connected to the base and adapted to engage said arm.

6. A lamp-support comprising a base, a downwardly-extending arm pivotally connected thereto and provided with an opening and a slot for supporting the lamp, flanges at the sides of the slot below the pivotal point thereof adapted for steadyng the lamp, and a lock connected to the base and adapted to engage the arm.

7. A lamp-support comprising a base, a downwardly-extending arm pivotally con-

nected thereto and provided with an opening and a slot for supporting the lamp, padded flanges at the sides of the slot for noiselessly steadyng the lamp and a buffer carried by the said arm.

In testimony whereof I have hereunto set my hand in the presence of two subscribing witnesses.

SAMUEL DAVIS.
